CONTROL APPARATUS

Randall Gillis, Westfield, N. J., assignor to
 Western Electric Company, Incorporated, New
 York, N. Y., a corporation of New York

Application January 14, 1939; Serial No. 250,977

8 Claims.

(Cl. 136—4)

This invention relates to control apparatus, and more particularly to thermocouple apparatus for controlling the temperature of heated material enclosed in a wall and while under pressure.

In the manufacture of electrical conductor cables it is frequently desirable to provide such a cable with a seamless sheath of lead, lead alloy, or other suitable material. In many cases this is done by passing a cable core or cable through a suitable die mounted in the die block of an extrusion press so that the sheath is formed by the action of the press, about the core or cable as the latter passes through the die. Such a press ordinarily has an extrusion cylinder to which molten sheathing material is supplied. The material is allowed to cool to a nearly solid or quite solid condition before it is forced out of the cylinder through the die by a ram suitably driven by hydraulic or other power. In such cases there is an optimum temperature for the sheath material at the time of extrusion to effect the production of the most satisfactory sheath, which temperature will vary with the nature and composition of the material and also perhaps with the dimensions and thickness of the cable and sheath. This optimum temperature will however, in general, be constant for any one set of such conditions. It is therefore important to be able to know the temperature of the material in the cylinder at any time during the process. However, considering that the cylinder of such a press is necessarily a massive piece of steel and that the material contained in it is under relatively enormous pressures (which in the case of a lead sheathing press may be of the order of 55,000 lbs. per square inch), so that the material behaves in some ways like a fluid, transmitting the pressure in all directions, it is not practicable to introduce any temperature reporting instrument into the body of the material itself, and extreme care must be taken as to the sealing of any openings in the wall of the cylinder itself and as to the structure of an instrument exposed directly to such pressure.

An object of the present invention is to provide simple, accurate, reliable and safe means to report the temperature of heated material in a container and under pressure.

With the above and other objects in view, one embodiment of the invention may comprise a generally rod-shaped thermocouple or analogous device, housed in a tube of metal constructed to be mounted in a suitable bore in the wall of a container, the temperature sensitive end of the

thermocouple being supported in a body of heat insulating material to separate the thermocouple from the tube and to close the end of the tube while exposing the tip of the thermocouple either nakedly or through a heat conductive metal shield to material in the container.

Other objects and features of the invention will appear from the following detailed description of one embodiment thereof in a temperature responsive device intended to be mounted in the wall of the cylinder of a lead cable sheathing press, taken in connection with the accompanying drawings in which the same reference numerals are applied to identical parts in the several figures and in which

Fig. 1 is a partial view in front elevation of a lead cable sheathing press having therein a temperature reporting device constructed in accordance with the invention;

20 Fig. 2 is a view partly in section on the line 2—2 of Fig. 1;

Fig. 3 is an enlarged detached end view partly in section of the device;

25 Fig. 4 is a section on the line 4—4 of Fig. 3;

Fig. 5 is a section on the line 5—5 of Fig. 4;

Fig. 6 is a fragmentary view, similar to a part of Fig. 4, of a modified form;

Fig. 7 is a view corresponding to Fig. 3 of a second modified form; and

30 Fig. 8 is a section on the line 8—8 of Fig. 7.

In the present disclosure, so much of a lead cable sheathing press is shown in Figs. 1 and 2 as is necessary to an understanding of the invention proper. Such a press includes as a principal member of its organization a hollow cylinder 20 into which molten lead is poured from above. The lead is allowed to cool to a temperature of the order of 350°—400° F., at which it sets to a solid or nearly solid condition. A ram is then introduced and forced down, causing the lead to be forced through an opening in the bottom of the cylinder into a chamber whence it is extruded through a die mounted in the chamber wall. The pressure in the cylinder required to effect this will be of the order of 55,000 lbs. per square inch.

To be able to determine the temperature of the lead in the cylinder at any time, the device shown in Figs. 3, 4 and 5 is mounted in an appropriate bore 21 formed in the wall of the cylinder, preferably radially and extending through the wall. As shown in Figs. 1, 2 and 3, the device has a tubular housing 30 of steel or other suitable material fitting closely into the bore 21 throughout most of its length and locked

into place in the bore by a screw thread 31 on the outer portion of the tube. A combined head and housing 32 is mounted on the tube 30, on the extreme outer end as shown, and is rigidly locked to the tube by means of one or more key screws 33. The outside of the member 32 is formed as a hexagonal bolt head and thus the member may serve as a head for the screw 31 when the tube 30 is being seated in or removed from the bore 21. A heavy nut 34 is threaded on the thread 31 outside of the head 32 and a spacing washer 35 is placed loosely around the tube 30 inside of the nut 34.

Under the heavy pressure of operation of the press, a certain amount of lead will sometimes be forced, more or less far, as a film between the walls of the tube 30 and of the bore 21, making it difficult to withdraw the tube after the thread 31 has been retired out of engagement with the corresponding thread of the bore. The nut 34 is provided to act as an extractor to complete the withdrawal of the tube. The washer 35 is provided and is interchangeable for others of different thicknesses to permit of placing the device in cylinders having walls of different thicknesses.

A thermocouple 36 consisting of an outer closed ended tube 37 and an inner coaxial rod or wire 38 welded together at 39 where the inner end of the rod rests against the end wall of the tube, is housed coaxially in the tube 30 and out of contact therewith throughout its length. The tube 37 and rod 38 are of dissimilar metals, as is customary in a thermocouple, one, for example, being of iron and the other of the 60% copper-40% nickel alloy known as "constantan." The inner tip (the heat responsive or "hot" junction) of the thermocouple is flush with the inner end of the tube 30 and thus is exposed directly, when the tube 30 is in place in the bore 21, to contact with the contents of the press cylinder 20. The inner end of the couple is both supported in and insulated from the tube 30 by a centrally bored cylindrical plug 40 of some suitable heat insulating material such as the hard burned porcelain known as "lavite," which also serves to close the end of the tube 30 and is preferably secured in place with pins 41 and backed by a steel supporting ring 42 seated against a corresponding shoulder in the inside wall of the tube 30.

Preferably the tube 37 is spaced from the tube 30 throughout the rest of the distance from the ring 42 to the housing 32 by means of a helical coil of steel wire 43. The contact of this wire with the tube 30 on one side and with the tube 37 on the other are both line contacts and the transfer of heat through the wire from one tube to the other is negligible.

The outer end of the tube 30 is closed by a plug 44 of steel or other suitable material, axially bored to receive and radially support the outer end of the tube 37. The bore of this plug is a three-lobed aperture, as shown, so that the contact of the tube 37 with the plug 44 is only along a line at the end of each of the radially inwardly projecting lugs which separate the lobes of the aperture. The outer extremity of the tube 37 abuts against and is longitudinally supported by a steel member 45 held in place by the housing lid 46 and the bolts or screws 33. The electrical conductors 47 and 48 respectively attached to the tube 37 and rod 38 are brought out, preferably through a side wall of the housing 32, by any suitable means, and pass through the mem-

ber 45 by means of a central hole or a radial slot therein.

In case the pressure at the inner end of the device is too great to be born by the tip of the thermocouple 36, the structure may be modified as shown in Fig. 6. Here a protective member or plug 49, of highly heat conductive material, such as copper, is set into the lavite plug 40 to close the end of the bore therein, and the tip of the thermocouple is seated in an axial recess in the plug 49. The ring 42 is replaced by a lavite ring 142 and a flange on the open end of the plug 49 is held between the ring 142 and the plug 49 to prevent the plug 49 from being displaced in either direction.

Another modified form is disclosed in Figs. 7 and 8. Here the structure of Figs. 4 and 6 is generally adapted to permit of the use of another type of thermocouple. In this case the thermocouple consists of two parallel wires or rods 137 and 138 of dissimilar metals, held out of contact with each other and with the walls of the tube 30 by doubly perforated beads, or analogous members, 143, of electrical and heat insulating material such as lavite. The tips of these wires are threaded through parallel bores in the lavite plug 242, brought together, welded together, and soldered to the copper plug 49 at 139.

In the structure of Fig. 4, the tip of the thermocouple 36 is positioned to be flush with the inner ends of the plug 40 and of the tube 30 so that there will be no recess or chamber at the inner end of the device into which any appreciable amount of the cylinder contents can be lodged. Hence the thermocouple is always exposed to the flowing and changing contents of the cylinder and is not shielded by a fraction of the contents of a different temperature state than the main body. The same effect, substantially is achieved in Figs. 6 and 8 by making the end faces of the plug 49, the plug 40 and the tube 30 mutually flush. Needless to say that when the device is seated in the bore 21 its inner end should be substantially flush with the cylinder wall, for the same reason.

The embodiments of the invention above disclosed are illustrated and may be modified and departed from in various ways without departing from the spirit and scope of the invention as pointed out in and limited only by the appended claims.

What is claimed is:

1. A device for reporting the temperature state of material in a container, comprising a tubular metal housing to extend through and seal an aperture in a container wall, temperature responsive means housed within the housing and having a temperature sensitive element at the inner end of the housing to be affected by the temperature state of material in the container, and a rigid sleeve of hard insulating material between the element and the housing but not covering the tip of the element, to render the inner end of the device flush across and prevent deposit of material therein.

2. A device for reporting the temperature state of material in a container, comprising a tubular metal housing to extend through and seal an aperture in a container wall, temperature responsive means housed within the housing and having a temperature sensitive element at the inner end of the housing and flush therewith and uncovered thereby to be affected by the temperature state of material in the container, and a rigid sleeve of hard insulating material between

the element and the housing but not covering the tip of the element, to render the inner end of the device flush across and prevent deposit of material therein.

3. A device for reporting the temperature state of material in a container, comprising a tubular metal housing to extend through and seal an aperture in a container wall, a thermocouple housed within the housing and having the juncture of the thermocouple at the inner end of the housing to be affected by the temperature state of material in the container, and a rigid sleeve of hard insulating material between the juncture and the housing but not covering the tip of the juncture, to render the inner end of the device flush across and prevent deposit of material therein under pressure.

4. A device for reporting the temperature state of material in a container, comprising a tubular metal housing to extend through and seal an aperture in a container wall, a thermocouple housed within the housing and having the juncture of the thermocouple at the inner end of the housing and flush therewith and uncovered thereby to be affected by the temperature state of material in the container, and a rigid sleeve of hard insulating material between the juncture and the housing but not covering the tip of the juncture, to render the inner end of the device flush across and prevent deposit of material therein under pressure.

5. A device for reporting the temperature state of material in a container, comprising a tubular housing to extend through and seal an aperture in a container wall, a thermocouple housed within the housing and having a guard of highly heat conductive material positioned on the juncture thereof and having the guard positioned at the inner end of the housing to be affected by the temperature state of material in the container, and a rigid sleeve of hard insulating material between the guard and the housing to render the inner end of the device flush across and prevent deposit of material therein under pressure.

6. A device for reporting the temperature state of material in a container, comprising a tubular housing to extend through and seal an aperture in a container wall, a thermocouple housed within the housing and having a guard of highly heat conductive material positioned on the juncture thereof and having the guard positioned at the inner end of the housing and flush therewith and uncovered thereby to be affected by the temperature state of material in the container, and a rigid sleeve of hard insulating material between the guard and the housing to render the inner end of the device flush across and prevent deposit of material therein under pressure.
- 10 7. A device for reporting the temperature state of material in a container, comprising a tubular metal housing to extend through and seal an aperture in a container wall, a rod-shaped thermocouple unit within the housing and having its temperature sensitive junction at the inner end of the housing to be affected by the temperature state of material in the container, and a rigid sleeve of hard insulating material between the temperature sensitive junction and the housing
- 20 25 but not covering the tip of the junction, to render the inner end of the device flush across and prevent deposit of material therein under pressure.
8. A device for reporting the temperature state of material in a container, comprising a tubular metal housing to extend through and seal an aperture in a container wall and having an open inner end, a rod-shaped thermocouple unit within the housing and having its temperature sensitive junction at the open inner end of the housing to be affected by the temperature state of material in the container, and a rigid sleeve of hard insulating material between the temperature sensitive junction and the housing but not covering the tip of the junction, to render the inner end of the device flush across and prevent deposit of material therein under pressure.
- 30 35
